C. SMITH

INDIRECT WATER HEATING APPARATUS

Filed April 9, 1923

Inventor:

Chetwood Smith

By Southgate & Southgate
attorneys.

UNITED STATES PATENT OFFICE.

CHETWOOD SMITH, OF WORCESTER, MASSACHUSETTS.

INDIRECT WATER-HEATING APPARATUS.

Application filed April 9, 1923. Serial No. 630,876.

To all whom it may concern:

Be it known that I, CHETWOOD SMITH, a citizen of the United States, residing at Worcester, in the county of Worcester and 5 State of Massachusetts, have invented a new and useful Indirect Water-Heating Apparatus, of which the following is a specification.

This invention relates to apparatus for 10 heating water indirectly by means of circulating heating water from a main water heater or boiler. In certain types of steam boilers it is desirable that the upper connection for the indirect heater be made at 15 the extreme top of the boiler, where provision is most commonly found for conveniently admitting the connecting pipe within the boiler. This point of connection is above the water level of the boiler, so that 20 the connecting pipe to the indirect heater must be downwardly extended within the boiler to a point below the normal water level.

It is one object of my invention to provide 25 an improved arrangement of connections and valves for such an indirect heating apparatus, by the use of which the circulation of water through the indirect heater may be conveniently started by a siphon action.

30 In many installations of indirect heating apparatus the storage tank is necessarily placed above the level of the indirect heater and another object of my invention is to provide an improved construction and arrangement 35 of connections by which cold feed water will be admitted only through the indirect heater when hot water is withdrawn from the storage tank, thus materially reducing the cooling of the water remaining 40 in the storage tank. A further feature of my invention provides for the delivery of partially heated feed water from the indirect heater to the lower portion only of the storage tank.

45 My invention further relates to arrangements and combinations of parts which will be hereinafter described and more particularly pointed out in the appended claims.

50 A preferred form of the invention is shown in the drawings in which—

Fig. 1 is a front elevation of water heating apparatus embodying my improvements; and

55 Figs. 2 and 3 are enlarged detail views of certain valves used in connection therewith.

Referring to the drawings, I have shown

a main water heater or boiler 10 of the horizontal tubular type and having a normal water level W. I have also shown an indirect heater 11 comprising a casing or heating chamber and a heating coil or conduit 12 mounted therein. The casing of the indirect heater 11 has an upper connection by a pipe 13 to the boiler 10 and a lower connection thereto by a pipe 14.

The pipe 13 passes through a flange 15 at the top of the boiler 10 and extends to a point below the normal water level W as clearly indicated in Fig. 1. The pipe 14 is connected into the lower portion or water leg 16 of the boiler and is provided with a valve 17 for a purpose to be described. An outlet pipe 18 is also connected into the pipe 14 and is provided with a valve 19.

When it is desired to start the circulation 75 of water through the indirect heater, the valve 19 is closed and the valve 17 is opened, thus allowing the water to rise through the indirect heater 11 into the pipe 13 as high 80 as the water level W. The valve 17 is then 85 closed and the valve 19 opened, permitting water to flow from the discharge pipe 18 with a siphon action, withdrawing water from the boiler 10 through the upper pipe 13 and exhausting the air and steam from the 90 indirect heating apparatus. When the air and steam are fully exhausted, the valve 19 is closed and the valve 17 is opened and the water thereafter circulates through the 95 indirect heater in the usual manner. I am 100 thus able to successfully operate an indirect heater where certain parts of the connections are located above the water level in the main heater 10. If the difference in elevation is considerable, a low steam pressure in the boiler will help materially in starting the 105 siphon action.

The water from the coil or conduit 12 is delivered through a pipe or riser 20 to the upper part of a storage tank 21, from which 110 it may be drawn through an outlet pipe 22 for domestic and other purposes. An inlet or feed pipe 23 supplies cold water to take the place of any hot water withdrawn through the outlet pipe 22. A branch connection 24 connects the feed pipe 23 with the lower part of the storage tank 21 and a second branch connection 25 connects the riser 20 to the lower part of the storage tank.

115 Normally open check valves 26 and 27 are placed in the pipes 20 and 24 respec-

tively and a normally closed check valve 28 is placed in the branch connection 25. The check valves 26 and 27 are of similar construction and one of them is shown in detail 5 in Fig. 2.

When no water is being withdrawn from the storage tank 21, the water will circulate in its normal path from the coil 12 through the riser 20 to the top of the tank 21 and 10 from the bottom of the tank 21 through the pipe 24 and the feed pipe 23 back of the coil 12. The check valve 28 remains closed and the flow of water is not sufficiently active to close the check valve 26.

15 If, however, water is withdrawn from the tank 21 through the pipe 22, a much more rapid inflow of water occurs in the pipe 23. The pressure of this inrushing cold water upward in the pipe 24 raises the 20 valve 27, thus closing the pipe 24 and preventing direct introduction of cold water into the tank 21. Similarly the rapid upward flow of water to the riser 20 closes the 25 check valve 26 and prevents discharge thereof to the top of the tank 21.

The incoming cold water is thus forced to pass through the heating coil 12 and to enter the tank 21 through the branch connection 25 by opening the check valve 28. 30 In this way the cold water is partially heated by passing through the coil 12 and is delivered to the lowest and coolest part of the tank 21, leaving the relatively hot water in the top of the tank substantially undisturbed. As soon as the feed of cold water ceases, the check valves 26 and 27 open and the check valve 28 closes, and the normal circulation of water through the pipes 20 and 24 is resumed. Water may thus be 40 drawn from the storage tank 21 without greatly reducing the temperature of the water remaining in the tank by the direct mixture of cold water therewith in the hotter portions thereof.

45 If the inflow of feed water is too slight to raise the check valve 26 the feed water may enter the top of the tank 21 through the riser 20, but in such small amount that it is not objectionable. The temperature of 50 this small amount of water is also materially raised in passing through the indirect heater 11.

Having thus described the several features of my invention and the advantages thereof, I do not wish to be limited to the details herein disclosed otherwise than as set forth in the claims but what I claim is:—

1. Means for heating water indirectly having, in combination, a main water heater, an indirect heating apparatus comprising an indirect heater and upper and lower connections for the circulating heating water between said main heater and said indirect heater, said upper connection 60 entering said main heater above the normal 65

water level therein and extending below said normal water level within the heater, and means to start the circulation of heating water in said indirect heating apparatus. 70

2. Means for heating water indirectly having, in combination, a main water heater, an indirect heating apparatus comprising an indirect heater and upper and lower connections for the circulating heating water between said main heater and said indirect heater, said upper connection 75 entering said main heater above the normal water level therein and extending below said normal water level within the heater, and means to start the circulation of heating water in said indirect heating apparatus, said latter means comprising a discharge outlet for said indirect heating apparatus, a valve to close said outlet, and a second valve between said first valve and the lower point of connection to said main heater. 80

3. Means for heating water indirectly having, in combination, a main water heater, an indirect heating apparatus comprising an indirect heater and upper and lower connections for the circulating heating water between said main heater and said indirect heater, said upper connection entering 85 said main heater above the normal water level therein and extending below said normal water level within the heater, and means to start the circulation of heating water in said indirect heating apparatus, said latter means comprising a discharge pipe attached to said lower connection, a valve for said pipe, and a second valve in 90 said lower connection between said first valve and said main water heater. 95

4. Indirect water heating apparatus comprising a storage tank, an indirect heater having a conduit therein for the water to be heated, a supply pipe for feed water under pressure and connections between said conduit, said tank and said supply pipe providing a normal path of delivery of heated water from said conduit to the upper part of said storage tank, and providing a second path of delivery from said conduit to the lower part of said storage tank when cold feed water is admitted from said supply pipe to said apparatus. 100

5. Indirect water heating apparatus comprising a storage tank, an indirect heater having a conduit therein for the water to be heated, a supply pipe for feed water under pressure and connections between said conduit, said tank and said supply pipe providing a normal path of delivery of heated water from said conduit to the upper part of said storage tank, and providing a second path of delivery from said conduit to the lower part of said storage tank when cold feed water is admitted from said supply pipe. 110

ply pipe to said apparatus, said feed water passing through said conduit before entering said storage tank.

6. Indirect water heating apparatus comprising a storage tank, an indirect heater having a conduit therein for the water to be heated, a supply pipe for feed water under pressure and connections between said conduit, said tank and said supply pipe providing a normal path of delivery of heated water from said conduit to the upper part of said storage tank, said connections also including a branch passage from said conduit to the lower part of said storage tank providing a path of delivery for feed water admitted to said apparatus from said supply pipe, and a return connection from said storage tank to said conduit, having means therein to prevent a flow of feed water through said return connection direct to said storage tank.

7. Indirect water heating apparatus comprising a storage tank, an indirect water heater having a conduit for the water to be heated, a feed pipe connected to the lower part of said conduit, a riser from the upper part of said conduit to the upper part of said storage tank, a branch connection from said feed pipe to the lower part of said storage tank, a second branch connection from said riser to the lower part of said storage tank, normally open check valves in said first branch connection and said riser, and a normally closed check valve in said second branch connection, said normally open valves being closed by a rush of feed water into said riser or said first branch connection.

In testimony whereof I have hereunto affixed my signature.

CHETWOOD SMITH.
